UNITED STATES PATENT OFFICE.

THOMAS VICARS, JOHN VICARS, AND EDWARD LYNTON VICARS, OF EARLESTOWN, ENGLAND.

OVEN.

1,148,265.

Specification of Letters Patent. Patented July 27, 1915.

Application filed February 26, 1913. Serial No. 750,765.

To all whom it may concern:

Be it known that we, THOMAS VICARS, JOHN VICARS, and EDWARD LYNTON VICARS, subjects of the King of Great Britain, residing at Earlestown, in the county of Lancaster, England, have invented new and useful Improvements in Ovens, of which the following is a specification.

This invention relates to those ovens which have longitudinal flues above and below the baking chamber arranged in zigzag manner and our object is to provide means whereby the flues may readily be changed from the zigzag arrangement to a number of separate straight flues or vice-versa thus making the oven more suitable for either quick or slow baking of biscuits, &c.

The invention is hereafter described with reference to the accompanying drawings whereon—

Figure 1 is a longitudinal section at the line A A on Fig. 2. Fig. 2 is a horizontal section at the line B B on Fig. 1. Fig. 3 is a horizontal section at the line C C on Fig. 1. In all these the middle portion of the oven is broken away. Figs. 4 and 5 are transverse sections at the lines D D and E E respectively on Fig. 1, all of an oven constructed according to our invention.

30 *a* are the outer walls of the oven.

b, *b'*, *c*, *c'*, *d*, *d'*, *e*, *e'*, *f*, *f'*, *g*, *g'*, are a number of straight flues arranged longitudinally above and below the oven *h* in sets, the two flues of each of the top sets communicating with one another at both ends and the two flues of each of the bottom sets communicating with one another at one end. Some of the flues *b'*, *c'*, *d'*, *e'*, *f'*, and *g'* are provided with inlet dampers *i* so that the gases from the fireplace *j* can be shut off therefrom, such gases then entering the other flues *b*, *c*, *d*, *e*, *f*, *g*, of the sets and passing in a zigzag course, as shown by the arrows, to the outlets *k* from the flues *b'*, *c'*, *d'*, *e'*, *f'*, *g'*, which are also provided with dampers *l*. Each bottom set of flues *e*, *f*, *g*, is also open at one end to a common outlet *m* provided with a damper *n* which is closed when the flues are being worked in zigzag.

50 Each top set of flues *b*, *b'*, *c*, *c'*, *d*, *d'*, is open at both ends to common outlets *o* provided

with dampers *p* which are closed when the flues are worked in zigzag. To operate as straight flues the end common outlet dampers *n*, *p*, are opened the other outlets *k* closed and all the inlet dampers *i* opened. The fire gases then enter direct or from uptakes into each straight flue and pass direct to the end outlets *m*, *o*. Flues and dampers are also provided, in any usual way, where- 60 by the gases can be passed directly from the fireplace to the chimney when desired without passing through the oven flues.

We claim;—

1. The combination in an oven of longitudinal straight flues arranged in sets, the flues in a set communicating with each other at certain ends, and one flue of each set having a damper controlled inlet and outlet, and a damper controlled outlet common to 70 all of the flues of a set.

2. A bake oven including a wall structure having a source of heat and an oven space, longitudinal flues arranged in sets above and below the oven, certain of the flues of each 75 set communicating with each other at corresponding ends thereof, means to establish communication directly with all of the flues of the sets, outlets designed to be placed in communication with the flues directly or 80 adapted to be cut off therefrom and additional outlets designed to be placed in communication with certain of said flues not placed in direct communication with the source of heat.

3. An oven having a baking chamber and a source of heat supply, longitudinal flues above and below said chamber, said flues being arranged in sets, the flues of each upper set communicating with each other at their 90 ends and the flues of each lower set communicating with each other at one end of the oven, inlet dampers for each alternate flue of each lower set, outlets for each of the last mentioned flues adapted to be placed in communication with the other flues of the lower sets through the flues provided with the inlet dampers when the latter are closed or in direct communication with the source of heat when said dampers are open, damper 100 controlled outlets communicating with the ends of the flues of the lower sets which are

in communication, the alternate flues of the upper sets being also placed in communication with said first mentioned outlets and means to place all of the flues of the upper sets in direct communication with the source of heat while the first named outlets are closed and to establish the direct outlets at the ends of the flues of the upper sets.

In testimony whereof we have signed our

names to this specification in the presence of 10
two subscribing witnesses.

THOMAS VICARS.

JOHN VICARS.

EDWARD LYNTON VICARS.
